UNITED STATES PATENT OFFICE.

HARRY H. EVERHARD, OF CANTON, OHIO.

WINDOW SCREEN.

Application filed April 19, 1927. Serial No. 184,871.

The invention relates to window screens and more particularly to a screen having a frame wherein the screening fabric is removably held in place.

5 The object of the invention is to provide a screen having a substantially channel-shaped frame, the screening fabric being arranged to be removably connected to the frame by attaching the corners of the screening fabric to 10 the corner portions of the frame with a removable attaching clip, the edges of the screening fabric being clamped within one side of the channel frame by means of rods having spaced bends or projections therein 15 whereby the rods may be quickly and readily snapped into place within the channel frame, clamping the adjacent edge of the screening fabric within one side of the frame.

Other objects of the invention include the 20 provision of a screen frame which is open upon its inner side, permitting a circulation of air through the same at all times in order to keep the frame dry and free from moisture, thus preventing corrosion of the parts; and 25 to provide a simple and inexpensive method of forming and assembling the frame.

An embodiment of the invention is illustrated in the accompanying drawings, in which

30 Figure 1 is an elevation of the inner side of the improved window screen;

Fig. 2, an enlarged section on the line 2—2, Fig. 1;

Fig. 3, a detail perspective view of one of 35 the corner clips;

Fig. 4, a detached perspective view of one of the corner plates of the frame;

Fig. 5, a fragmentary elevation of a portion of one of the clamping rods;

40 Fig. 6, an enlarged fragmentary elevation of one corner of the frame, before the corner plate is connected thereto;

Fig. 7, a similar view showing the completed corner of the frame, and

45 Fig. 8, a fragmentary elevation of the inner side of one corner portion of the screen, parts being broken away for the purpose of illustration.

Similar numerals refer to similar parts 50 throughout the drawings.

The frame indicated generally at 1 is composed of members substantially channel-

shaped in cross section. The outer edge flange of each channel member is inwardly curved as shown at 3 and then extends from the web portion 7 as at 2. The inner edge flange of each channel member is inwardly curved half-round as shown at 4 and then extends inwardly from the curved portion 4 at an angle from the web portion 7 as at 5. The curved portions 3 and 4 thus form retaining grooves for a clamping rod to be hereinafter described.

As shown in Fig. 2, the outer flange portion 2 extends from the web portion 7 of the channel member a greater distance than the angular flange 5 thereof, which flange 5 terminates at a point spaced from the plane shown at 6 passing through the outer edge of the portion 2 parallel with the web portion 7 of the channel frame. The web portion 7 and the plane 6 are also parallel with the normal plane of the screen as shown at 12.

Although this frame may be made up in any well known manner, it is preferred to form 75 the frame of a single strip of metal having angular cut-out portions at the corners whereby the frame may be formed or bent into rectangular shape, the edges of these cut-out portions meeting as shown at 8 in Fig. 6.

An aperture 9 may be formed upon each side of each cut-out portion to receive the tangs 10 of the corner plates 11 which tangs are bent back upon the inner side of the frame, thus forming a rigid one-piece frame. 85 If desired, the apertures 9 and tangs 10 may be dispensed with and the plates 11 may be welded or otherwise connected to the corners of the frame.

When the corner is formed as above described, the channel member curved portions 3 of each corner member form an outer flange apex as at 20, and the channel member curved portions 4 form an inner apex 21.

The screen fabric 12 is attached by laying 95 the same over the inner side of the frame and first connecting the four corners thereof to the frame by means of the notched clips 13.

The notch 14 of each clip engages the corner portion of the fabric and bends the same 100 down beneath the corner of the flange 5 of the frame and clamps the same against the inner flange apex 21, while the nose portion 22 of each clip 13 engages inside the

outer flange apex 20 as shown at 23. For the purpose of quickly and easily removing these corner clips, when it is desired to remove the screen fabric, a loop 15 may be pressed or 5 stamped upon each clip.

The free edges of the screen fabric may then be bent down over the edges of the flanges 5 of the channels which go to make up the frame, said channels being substantially parallel to the normal plane of the screen, and the 10 clamping rods 16 are then placed in position. Each of these clamping rods may be provided with the projections or loops 17 at spaced intervals, the portions 18 of the rod, between 15 said loops or projections being preferably bowed slightly outward as best shown in Fig. 5.

These normally bowed portions 18 of the rod engage the downturned edge portion of 20 the screen fabric against the retaining groove formed by the curved flange portion 4, and the projections or loops 17 are then pressed downward into and engage the retaining groove formed by the curved flange portion 25 3. The bowed portions 18 are thus sprung when the rod is retained within the channel so that said portions are maintained parallel with the flange groove 4, thereby maintaining 30 a clamping contact against the screen fabric throughout the entire length of said portions. Of course it is understood that the natural inherent resiliency of such a metal rod will cause the same to again become normally bowed as at 18 when the rod is removed 35 from the channel.

With this construction of frame it will be seen that when the screen is placed in position upon the outside of a window frame, the only portion of the screen which engages the 40 window frame will be the inner edge of the flange 2, as shown in Fig. 2, the broken line 6 representing the plane of the window frame.

As shown in this figure, the screen fabric and the remaining portion of the frame are all 45 spaced from the window frame, thus permitting a circulation of air through the interior of the channel frame at all times in order to quickly dry any moisture which may enter the same and prevent corrosion of the frame 50 and screen.

When it is desired to remove the screen fabric in order to replace the same, it is only necessary to remove the clamping rods 16 and the corner clips 13 when the entire screen 55 fabric may be lifted from the frame and a new fabric placed therein in the manner above described.

I claim:

1. In screen frame construction, a channel 60 frame member substantially parallel with the normal plane of the screen, a clamping rod in said channel having spaced portions parallel with one portion of the channel and having spaced projections engaging another portion 65 of the channel, and a screen fabric edge por-

tion extending into said channel and secured therein between the parallel portions of the clamping rod and the channel.

2. In screen frame construction, a channel frame member substantially parallel with the 70 normal plane of the screen, one flange of the channel extending inward from one edge of the channel at an angle from the channel web portion, a clamping rod in said channel having spaced portions parallel with said angular flange and having spaced projections engaging the other channel flange, and a screen fabric edge portion extending over said angular flange and into said channel and secured 75 therein between the parallel portions of the clamping rod and the channel.

3. In screen frame construction, a channel frame member substantially parallel with the normal plane of the screen, one flange of the channel extending inward from one edge of 85 the channel at an angle from the channel web portion and the other flange of the channel extending away from the web portion a greater distance than the angular flange, a clamping rod in said channel having spaced 90 portions parallel with said angular flange and having spaced projections engaging the other channel flange, and a screen fabric edge portion extending over said angular flange and into said channel and secured therein between the parallel portions of the clamping 95 rod and the channel.

4. In screen frame construction, a channel frame member having in cross section, a web portion substantially parallel to the normal plane of the screen, and flange portions curved inwardly from the web portion forming retaining grooves, one flange extending inwardly from the curved portion at an angle from the web portion, and the other flange extending from the curved portion away from the web portion and terminating a greater distance from the web portion than the angular flange, a clamping rod in the channel having spaced portions parallel with one of said 100 retaining grooves and having spaced projections engaged in the other groove, and a screen fabric edge portion extending over said angular flange and into one of said 105 grooves and secured therein between the parallel portions of the clamping rod and the channel.

5. In screen frame construction, a channel frame member, a resilient clamping rod having spaced projections and portions between 110 the projections normally bowed away from the projections, a screen fabric edge portion extending into the channel, and the clamping rod retained in the channel clamping the screen fabric between the channel and the normally bowed rod portions, and the normally bowed rod portions being sprung when the rod is within the channel so that said portions are maintained parallel to the flange, thereby maintaining a clamping contact 115 120 125 130

against the screen fabric throughout the entire length of said portions.

6. In screen frame construction, channel frame members forming a corner having an outer flange apex and an inner flange apex, a corner clip having a nose portion and a notched portion, and a screen fabric corner edge portion extending into said channel cor-

ner, and the clip notched portion engaging the screen fabric and clamping said fabric 10 against the inner flange apex and the clip nose portion engaging the outer flange apex.

In testimony that I claim the above, I have hereunto subscribed my name.

HARRY H. EVERHARD.
